FIG. 1

FIG. 2

FIG. 3

FIG. 4

FIG. 5

INVENTOR.
PHILIP VEGA

ICE CHEST CART

SUMMARY OF THE INVENTION

My invention comprises a hollow rectangular container having a top lid and plurality of vertical partitions dividing the interior of the container into a plurality of compartments accessible by opening the top lid.

An additional lid covering one or more compartments but leaving at least one compartment exposed can be interposed between the top lid and the opening of the container.

The bottom of the container supports a horizontal axle rotatable about its own axis and having wheels secured to opposite ends whereby the container is easily movable on wheels from place to place. A handle can be pivotally secured to one side of the container for ease of movement thereof.

BRIEF DESCRIPTION OF THE DRAWINGS

In the drawings:

- FIG. 1 is a perspective top view of my invention;
 FIG. 2 is a side view thereof;
 FIG. 3 is a rear view thereof;
 FIG. 4 is a cutaway perspective view of my invention; and
 FIG. 5 is a bottom view thereof.

DETAILED DESCRIPTION OF PREFERRED EMBODIMENT

Referring now to FIGS. 1-5, a hollow rectangular parallel-piped body 10 extends horizontally. The body is open at its top and carries a drain 12 extending through its bottom surface. The body further has a plurality of spaced vertical partitions or interior walls 14 dividing the body into compartments. Walls 14 have holes 16 through which melted ice can pass to the drain. The body is insulated.

A top lid 18 is hingedly secured to the body. A portion of

the bottom surface of lid 18 is recessed as shown at 20 to accommodate a second lid 22 whereby at least one compartment is closed when lid 18 is opened and lid 22 is closed. All compartments are exposed when lids 18 and 22 are both raised at the same time. A horizontal stub 24 extends outward from the bottom of the container midway between its ends. A handle 26 is pivotally secured to the free end of the stub.

A horizontal axle 28 is rotatably journaled between two vertical end plates 32 extending downward from the bottom of the container at opposite ends thereof. Wheels 30 are secured to each end of the axle to complete the structure.

While I have described my invention with particular reference to the drawings, such is not to be considered as limiting its actual scope.

15 I claim:

1. An ice chest cart comprising:
 a hollow insulated rectangular parallel-piped body extending horizontally and open at the top,
 a horizontal axle freely rotatable about its own axis and supported from the bottom of said body;
 a pair of wheels secured to opposite ends of said axle;
 handle means secured to said body;
 a first lid having a recess in its bottom surface secured to said body to seal the top opening of said body;
 20 a plurality of spaced apart vertical walls in said body to divide the interior of said body into compartments; and
 a second lid secured to said body disposed in said recess in said first lid and cooperable with the top of at least one of said compartments to seal the top opening of said at least one compartment when said first lid is open thereby to maintain a seal for said at least one compartment.
2. A cart as set forth in claim 1, wherein the body has a drain in its bottom portion.
3. A cart as set forth in claim 2 wherein some of the vertical walls in said body have holes therein.
